BACK BATH BRUSH

August Freidrich Sichelschmidt, 185 Parkside Drive,
Toronto, Ontario, Canada

Filed Oct. 14, 1963, Ser. No. 76,971

Term of patent 14 years

(Cl. D9—2)

The figure is a bottom perspective view of a back bath brush, showing my new design.

The side not shown has substantially the same appearance as the side shown. The top is substantially flat and plain.

I claim:

The ornamental design for a back bath brush, as shown and described.
